UNITED STATES PATENT OFFICE.

HERMANN BOCKHOLT, OF COLOGNE-DEUTZ, GERMANY.

PLUNGER PUMP.

Application filed August 14, 1926, Serial No. 129,253, and in Germany August 12, 1925.

Heretofore, plunger pumps have become known, in the pump body of which a detachable cylinder with suction and pressure valves therein is arranged which tightly separates the suction and pressure chambers.

According to the present invention, said cylinder is firmly held upon the bottom of the pump body by the pressure of the stuffing-box packing.

10 The pump body *a* contains the suction and pressure chambers *l* and *m* respectively with the suction and pressure conduits *n* and *o* thereon. The pump body *a* carries a detachable centrally arranged cylinder *b* tightly 15 separating said suction and pressure chambers by means of a packing ring *i* and carrying the suction and pressure valves while a hood *c* on the pump body serves as an upper plunger guide and as a guide for the 20 pressure valves *f* and contains a gland-ring *d* and the packing *e* of a stuffing-box.

A screw *g*, or a plurality of said screws, in the hood *c* act upon the gland-ring *d* and serve to tighten the packing *e* and thus the 25 plunger *h* in the cylinder *b*, and to press the latter, which projects with its upper end

into the hood directly beneath said packing, firmly upon the bottom of the pump body. A lower extension on the cylinder *b* beneath the suction valve *s* receives slots *x* for a passage of the pressure-liquid therethrough and is centrally held on the bottom of the pump body by means of an annular projection *k* of the latter.

What I claim, is:—

The combination, in a plunger pump, of a pump body having an annular projection on its bottom, a detachable centrally guided cylinder therein, suction and pressure valves in the latter, a hood on said pump body serving as an upper plunger and cylinder guide and as a guide for said pressure valves, a gland-ring and a packing of a stuffing-box in said hood, the upper end of said cylinder projecting into said hood directly beneath said packing, and means on said hood to tighten said packing and to press said cylinder firmly upon the bottom of said pump body within the annular projection thereon.

In testimony whereof I have hereunto set my hand.

HERMANN BOCKHOLT.
